ATTORNEY

UNITED STATES PATENT OFFICE

ERIK JOHAN BERGSTROM, OF CHICAGO, ILLINOIS

WEDGE

Application filed September 2, 1927. Serial No. 217,285.

This invention relates to improvements in wedges for general use. One object is to provide a wedge that is so constructed that it can be removed from the body into which it is driven, when desired, and that while in use is very durable and efficient even though it is of a type adapted for possible removal as set forth.

With the foregoing and other objects in view the invention consists in the combination and arrangement of parts to be herein-after fully described, particularly pointed out in the appended claim and illustrated in the accompanying drawing which forms a part of this application for patent and in which—

Fig. 1 is a view of the wedge in front elevation.

Fig. 2 is an edge view of the wedge, the core being shown in section.

Fig. 3 is an enlarged face view of the core employed.

Like reference characters denote corresponding parts throughout the several views.

It is frequently desired, for one reason or another, to remove wedges that have been in place for a greater or less period of time. With the ordinary wedge this is a difficult proposition unless damage to the body in which the wedge is driven is resorted to. The present wedge is designed with a view to making it readily removable when desired and this without sacrificing any of its efficiency while in use.

The wedge comprises a shell portion made preferably of sheet metal, the head of the wedge being integral with one of the sides thereof, and a core made of soft steel, this core being formed with a deep marginal notch and being adapted for removable disposal in the said shell.

The reference numeral 1 denotes the shell of the wedge which is wedge-shaped, the sides of the shell meeting only at the blade or cutting edge 2 and thereabove being spaced apart to form a cavity to receive the core, the shell being open along its lateral edges and one of the sides being integral with the flat head 3, the metal forming a rounded

portion 4 where the head 3 and integral side merge. The free edge 5 of the head is contiguous to and may project beyond one side of the shell so that it is possible to insert the point or blade of an instrument or tool, such as a screw driver, between the free end of the head 3 and the upper edge of this contiguous side.

A core 6, wedge-shaped, and formed with a deep notch 7 in its thick end is adapted for removable disposal in the shell, said core being introduced into the shell from either side thereof. In use the wedge is applied to the work in the usual manner and driven in with a hammer or maul. When it is desired to remove the wedge the free end of its head 3 is pried upward from the contiguous side so that the upper or notched end of the core is exposed. An instrument or tool is then applied to the notched portion of the core and the core rocked or oscillated laterally until it is worked loose or worked up to such a point that it may be engaged with pliers, or like tools, and removed from the shell. The sides of the shell may now be slightly bent together or toward each other when it may likewise be removed. Ordinarily little or no real damage is done the wedge by applying and removing it a number of times so that it may be used over and over again.

What is claimed is—

In a wedge, a shell having a head integral with one of its sides only and open along its lateral edges, and a core shaped to conform to the interior of said shell and having a deep marginal notch in its thick edge, said core being adapted for insertion in or removal from said shell through the open lateral edges thereof and its notched portion being accessible when said head is forced away from one of the sides of said shell.

In testimony that I claim the foregoing as my own I have hereto affixed my signature.

ERIK JOHAN BERGSTROM.
